UNITED STATES PATENT OFFICE.

LAURENTE RUPP, OF NEW YORK, N. Y.

RAZOR-BLADE HOLDER.

1,414,046.

Specification of Letters Patent. Patented Apr. 25, 1922.

Application filed November 2, 1918. Serial No. 260,773.

To all whom it may concern:

Be it known that I, LAURENTE RUPP, a citizen of the United States, and a resident of New York city, in the county and State of New York, have invented certain new and useful Improvements in Razor-Blade Holders, of which the following is a specification.

This invention relates to a holder of novel construction, by means of which the blades of safety razors may be securely held while being stropped or honed.

In the accompanying drawing:

Fig. 1 is a side view, partly in section of a razor blade holder embodying my invention;

Fig. 2 a longitudinal section on line 2—2 of Fig. 1;

Fig. 3 a cross section on line 3—3 of Fig. 1;

Fig. 4 a side view of a modification, with the handle broken away;

Fig. 5 a longitudinal section on line 5—5 of Fig. 4 showing the handle, and

Fig. 6 a cross section on line 6—6 of Fig. 4.

Referring more particularly to Figs. 1—3, the device comprises a tubular rod or shank 1 fitted into a handle 2. Rod 1 is provided with a pair of diametrically opposed longitudinal slits 3, which may extend to the free end of the shank. This end is threaded as at 4, and engaged by a nut 5 bearing against a tubular washer 6, that is slideable on the rod.

In use, nut 5 is slackened and a double edged razor blade 7 is passed through slits 3 in such a manner that the shank becomes centered upon the blade which thus projects laterally from the shank at both ends to an equal extent. The nut is then tightened up to crowd the washer against the blade and force the latter in turn against the ends of the slits, thus locking the blade to the shank.

By now grasping the handle, the blades may be readily passed over a stone or strop so as to sharpen or hone the same.

The handle 2 is preferably made hollow to

form a chamber adapted to be closed by a plug 8. This plug is provided with a pin 9 that enters the chamber and serves to loosen a suitable diamond dust preparation 10 which is contained therein and may be rubbed over the strop.

Figs. 4—6 show the device adapted for the reception of a blade having a single cutting edge. Here the tubular shank 1 is provided with but a single slit 3 into which the blade 11 is introduced in such a manner that its heel extends into the hollow of the shank 60 and rests against the inner unslotted portion thereof. The shank is as before, provided with a threaded end 4 carrying the nut 5 and washer 6.

It will be seen that with the device constructed as described, the blade may be readily locked to the handle, and after being locked, may be effectively sharpened or honed, without liability of cutting the operator's fingers, either while being fitted to the holder, or while being manipulated.

I claim:

A razor blade holder comprising a handle, a tubular shank forming an axial extension of said handle and having its outer end screw-threaded, said shank having a pair of diametrically opposite longitudinal slits arranged to accommodate a razor blade and to permit it to extend diametrically of said shank and beyond the same in opposite directions, said slits having their inner ends closed and located at a distance from said handle to form spaced bearing surfaces for one end edge of said razor blade, the outer ends of said slits being open to permit the introduction of said blade, a tubular sleeve slidably mounted upon said shank and arranged to engage the other end edge of said razor blade, and a nut threaded upon the screw-threaded end of said shank and adapted to press said sleeve against said blade, and the latter against the closed ends of the slits to clamp said blade against removal from said shank and to close the open ends of said slits.

LAURENTE RUPP.
